(57) **CLAIM**

The ornamental design for a stock pot, as shown and described.

DESCRIPTION

FIG. 1 is a front, right and top perspective view of a stock pot, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of area "9" in FIG. 2.

The broken lines shown in the drawings illustrate portions of the stock pot that form no part of the claimed design.

The dot-dash broken lines depict the boundaries of the enlargements that form no part of the claimed design.
